a corporation of Delaware

Application May 23, 1934, Serial No. 727,130

13 Claims. (Cl. 176—14)

The present invention relates to devices for intermittently varying the magnitude of an electrical current and comprises a combined incandescent lamp and flasher element therefor which, although particularly suitable for use as a flashing stop light for automobiles, may be advantageously employed wherever a flashing light is desired. The new combined lamp and flasher is of relatively simple and compact construction, may be readily designed to fit any standard lighting socket and may be rapidly and economically manufactured on a commercial scale by factory methods of production.

The principal object of the invention is to provide a combined flasher and lamp in which the flasher elements will take up a minimum of space while being of rugged construction and of positive operation.

Another object of the invention is to provide a combination of the above character in which the flasher elements are confined within an annular member secured about the base of the incandescent lamp.

A still further object of the invention is to provide a combination of the above character which may be economically manufactured on a commercial scale by relatively unskilled labor.

For an understanding of the invention reference may be had to the accompanying drawing of which:

Fig. 1 is a horizontal sectional view of the new flasher and incandescent lamp representing the preferred embodiment of the invention;

Fig. 1a is a detail sectional view illustrating a form of movable contact construction suitable for facilitating initial adjustment of the distance between contacts;

Fig. 2 is a vertical sectional view of the device of Fig. 1 taken along the line 2—2 thereof;

Fig. 3 is a fragmentary sectional view similar to Fig. 2 illustrating a simpler form of contact arrangement;

Fig. 4 is a fragmentary view similar to Fig. 1 illustrating a somewhat different construction of one element of the flasher; and

Fig. 5 is an enlarged sectional view taken along the line 5—5 of Fig. 4.

In accordance with the invention the flasher elements are carried in an annular cup-shaped member 2 secured about the upper end of the base 4 of an incandescent lamp bulb 6. The flasher in the embodiment of the invention illustrated in Figs. 1 and 2 includes a movable contact 8 mounted on or integral with the armature 10 of a permanent magnet 12, a fixed con-

tact 14 insulated from the base 4 and electrically connected to the filament 16 of the lamp and to a resistance wire 18, and an expansible wire 20, which may be a continuation of wire 18, and which is secured at one end to a spring strip 22.

The end of spring strip 22 remote from its connection with wire 20 is secured, as by welding, to the container 2 for support thereby and to make electrical connection therewith. Armature 10 is secured to spring 22 by screw 24, positioned adjacent the secured end of the spring. Spring strip 22 tends to move the armature against the tension of wire 20 and into its attracted position with contact 8 engaging contact 14. Wire 20 is adjusted by means hereafter to be described, to have a tension sufficient to maintain armature 10 in the retracted position when no current passes through the wire but to permit attraction of the armature when the wire expands under the heat generated by passage of current therethrough.

The provision of the biasing spring strip together with the permanent magnet insure substantially no sparking at the contacts and hence insures a relatively long life to the device.

Permanent magnet 12 is of such shape as to substantially fill the annular container 2 except for the segmental portion occupied by the armature 10. Preferably, in order to increase the magnetic attraction between armature and magnet, the armature in addition to the vertical wall portion carrying the contact 8 includes horizontal upper and lower wall portions 25 of segmental shape forming therebetween a channel for reception of the spring 22 and wire 20. Spring strip 22, as shown best in Fig. 2, is preferably of a slightly curved cross-section, concave toward the vertical wall of the armature, for a substantial portion of its length. This gives a stiffness to the spring which insures movement thereof throughout its length when the tension of wire 20 is reduced by expansion and insures, consequently, proper movement of the armature.

In the embodiment of the invention illustrated in Fig. 1, a bead 26 of glass or other insulating material is fused about the bend or right angle at the point of junction of wires 18 and 20. The end of an anchor or support wire 28 is fused into the bead 26 out of contact with wire 18—20. The other end of the anchor wire is passed through a small hole drilled in the side wall of container 2 in substantial alignment with wire 20. The purpose of anchor wire 28 is to support bead 26, in conjunction with wire 18—20, and to permit adjustment of the tension of wire 20 after as-

sembly of the flasher elements, as will be hereinafter described.

Container 2, while being of substantially annular form, is preferably so shaped at one portion thereof as to provide a small semi-cylindrical chamber 30 protruding beyond the circumference of the circular portion of the container and containing the bead 26. The base of container 2 is provided with a central circular aperture for reception of the base 4 of the lamp. Preferably, in the stamping of the container 2, the central aperture is not completely cut out but two oppositely disposed radial strips 32 are retained which, during assembly, are bent upwardly at right angles to the base and are then folded outward over the top of the magnet 12 to retain the same in position. When the lamp base 4 is of the bayonet type illustrated, having the prongs 34, slits are provided in the container base at each side of each strip 32 to permit the bending of the strips at points which will give clearance for the prongs 34 when the lamp base is inserted into the container. Magnet 12 is of course also suitably notched to permit clearance for the prongs.

Fixed contact 14 is mounted on a conducting strip or wire 36 which is electrically connected, within the lamp base, with the lead 37 of the lamp filament 16. Strip 36 is suitably insulated from base 4 as by means of an insulating strip 38. In the embodiment of the invention illustrated in Figs. 1 and 2 an end of wire 18 is welded directly to strip 36.

For initial adjustment of the distance between contacts 8 and 14, contact 8 may be wedge shaped, as indicated at 8a in Fig. 1a, so as to cause the effective distance between the contacts to be varied by slight relative rotation between container and lamp base during assembly of the device and while current is passed through the circuit including wire 20.

As an alternative to the contact construction above described, the arrangement of Fig. 3 may be advantageously employed. In this embodiment of the invention the separate contacts are omitted, the end of lead wire 37 is brought out through an insulating shield 39 and is silver plated as is also the armature 10. A small hook or prong 40 is formed in the end of the lead wire 37 which, when the end of resistance wire 18 is inserted therein, is pressed firmly thereupon to grip the same. The insulating shield 39 is formed with an aperture 42 therein and with a projecting shoulder 44 at the base of the aperture. The shoulder 44 serves to insulate wire 37 where it is led out from the base and also, during assembly, assists in the proper aligning of the parts when the bulb is inserted into the base. The silver plated end of lead 37 is brought out through the aperture 42 and bent, preferably while wire 18 is being pressed within the hook 40, into an outstanding loop engageable by the silver plated armature.

The operating distance between armature 10 and the looped portion of wire 37 may be varied during assembly either by relative rotation between the container and the lamp base while current is passed through wire 20, or by varying the shape of the loop to cause more or less extension thereof in the direction of motion of the armature. The substantial elimination of sparking effected by the combination of spring biasing means and permanent magnet, as heretofore described, makes possible, it is believed, the use of this simpler form of contact arrangement, name-

ly by the silver plating of the contacting parts with the consequent omission of the usual silver contact points.

In assembling the combined flasher and lamp the spring strip 22 carrying the armature 10 and having the end of wire 20 secured thereto, is first secured within the container 2. The anchor wire 28, which, together with bead 26, has been previously secured to wire 20, is then threaded through the aperture in the casing wall. The magnet 12 is then dropped into position over the upwardly bent strips 32 and these strips are bent outwardly over the magnet. The container and parts therein are then slipped upwardly over the prongs 34 of the lamp base into the position indicated in Figs. 2 or 3. Wire 18 is then threaded through any suitable insulating or spacing means, as, for example, through short sections of glass tubing 46, and its free end brought around and welded or otherwise electrically connected with strip or wire 36 or pinched to the silver plated end of lead wire 37. The distance between the contacts is then adjusted, either by relative rotation between the parts or in the case of the embodiment of Fig. 3, by such rotation or by varying the extension of the looped portion of wire 37 as above described, and the tension of wire 20 is adjusted by means of the anchor wire 28. When the desired tension has been obtained, wire 28 is welded to the container and the extra length thereof cut off. The container 2 is then welded to the base 4 to insure electrical contact therewith and to prevent relative movement therebetween. A suitable lid 48 is then secured over the portion of the container carrying the armature and bead 26. No cover is necessary for the rest of the device but preferably the space above the magnet is sealed with a suitable wax to protect the parts against jarring.

When the base 4 is inserted in the usual socket 40 therefor and a potential difference applied across the terminal 50 and the base 4, current will flow through filament 16, lead wire 37, wire 18-20 and spring 22 to the container 2 and base 4. This current heats wire 20 and causes it to expand 45 sufficiently to permit movement of the armature under influence of the spring 22 and of the attraction of magnet 12 into position to shunt resistance 18 and wire 20 as the circuit is now completed through the armature and spring 22 50 to the container and base. With the shunting of the wire 20, the wire cools and contracts and consequently reopens the contacts to again insert resistance 18 and wire 20 into the circuit. This cycle of operations continues as long as a potential difference is applied across the terminals of the lamp base and with proper selection of the value of the resistance 18 any degree of alternate dimming and brightening of the light from filament 16 may be obtained. Preferably the value 60 of resistance 18 is so chosen as to cause substantially no illumination of the lamp when the resistance is in series with the filament thereof.

The embodiment of the invention illustrated in Figs. 4 and 5 differs from that of Figs. 1 and 2 65 only in the means for adjusting the tension of wire 20. These means, in Figs. 4 and 5, include a sleeve 52 of insulating material positioned within chamber 30 about a vertical metal pin or rod 54 secured to the bottom wall of the container. 70 The sleeve 52 is provided with a passage 56 extending from the upper surface of the sleeve to a point on the cylindrical surface thereof. Wire 20 is wound for about one-half turn around the sleeve and is then threaded through passage 56 75

entering the passage at the side and leaving the same as resistance wire 18 at the top of the sleeve. A channel or groove 58 is formed across the top of the sleeve to receive a locking wire 60. 5 After assembly of the parts, the end of a suitably shaped welding iron is placed in the groove to turn the sleeve until the tension of wire 20 is that desired. The wire 60 is then spot-welded to pin 54 to prevent further rotation of the sleeve and to thereby maintain the desired tension.

10 The invention has now been described with reference to the preferred embodiment thereof and alternative arrangements of individual elements thereof have been described. It will be apparent that various changes in the construction of the parts could be made without departing from the spirit of the invention. Although the device has been illustrated as embodied in a 15 combination flasher and bayonet type lamp, such as is ordinarily used for automobile lights, obviously the particular type of base for the lamp is immaterial to the invention.

Furthermore, although the particular means herein illustrated and described for adjusting the tension of the controlling wire and the distance between contacts are intended for use during manufacture of the device, obviously these or analogous means could be employed for the making of adjustments at any time during use of the device. For example, the anchor or support wire of the embodiment illustrated in Fig. 1 need not be welded to the container but could be provided with means for varying its tension. Similarly, the rotation of the insulated sleeve of the embodiment of Figs. 4 and 5 to vary the tension of the controlling wire could be effected externally of the container.

It will be apparent from the above description that the invention provides a relatively compact and easily assembled combination lamp and flasher that may be economically manufactured and that is positive in operation. Although occupying but a relatively small amount of space and being confined within an annular container carried by the lamp, the flasher elements include a permanent magnet and a spring biased armature which together give a snap action to the opening and closing of the contacts, thus eliminating or substantially reducing sparking at the contacts and insuring positive operation of the flasher.

50 The following is claimed:

1. In a device of the class disclosed, the combination comprising a lamp having a base for insertion into a socket, a filament for the lamp connected to one terminal of the base and insulated from the other terminal of the base, an annular container positioned about said base and carried thereby, and means carried within said container and in electrical communication with said filament and with said other terminal of the base for flashing said filament when a potential difference is impressed across the terminals of said base.

55 2. A device according to claim 1 wherein said last mentioned means includes a pair of contacts, one electrically connected to said filament and the other connected to a terminal of the base, the container including a magnet and an armature therefor and said last mentioned contact being integral with said armature.

70 3. A combined incandescent lamp and flasher comprising in combination a lamp including a base and an incandescent filament, an annular

75 container mounted on said base, a permanent magnet within said container, an armature for said magnet supported within said container and carrying an electrical contact, a fixed contact carried on said base but insulated therefrom and electrically connected with said filament, said fixed contact being positioned to be engaged by said armature carried contact when said armature is in attracted position and means including an expansible wire and a resistance connected across said contacts and in series with said filament across the terminals of said base for causing alternate closing and opening of said contacts when a potential difference is impressed across the terminals of said base.

10 4. A combined electric lamp and flasher therefor comprising in combination a bulb including an incandescent filament, a base secured to said bulb and having an insulated terminal electrically connected to one end of said filament, a contact carried by said base but insulated therefrom and electrically connected to the other end of said filament, an annular container of conducting material positioned about said base and in electrical communication therewith, a resistor within said container connected in series between said contact and said base and means including a movable contact within said container and electrically connected thereto for intermittently shunting said resistor when a potential difference is impressed across said terminal and base whereby said resistor is intermittently cut in and out of circuit with said filament.

15 5. The combined electric lamp and flasher according to claim 4 wherein said last mentioned means includes means biasing said movable contact into position to engage said fixed contact and includes an expansible wire connected in series between said resistor and said movable contact, said biasing means operating to close said contacts upon expansion of said wire when heated by the passage of electric current therethrough, said wire when cold preventing such closure of the contacts.

20 6. The combined electric lamp and flasher according to claim 4 wherein said last mentioned means includes a permanent magnet, an armature therefor integral with said movable contact and an expansible wire which when cold prevents movement of said armature to attracted position 25 for engagement of said contacts, said wire and resistance being insulated from said container and connected in series across said contacts.

25 7. The combination with an incandescent lamp having a filament and base of an annular container secured about said base, a permanent magnet and an armature therefor within said container, a pair of contacts within said container, one electrically connected to said base and carried by said armature and the other positioned to be engaged by the armature carried contact when the armature is in attracted position, said last mentioned contact being insulated from said base and electrically connected with said filament, and an expansible resistance wire electrically connected across said contacts, said wire, when cold, mechanically preventing movement of said armature to contact closing position.

30 8. The combination according to claim 7 including an insulating bead within said container and secured to said wire and means secured to said bead and passing through the wall of said container for adjusting the tension of said wire.

35 9. The combination according to claim 7 where- in said annular container is shaped to provide a

semi-cylindrical chamber adjacent said armature and wherein a member of insulating material having a passage therein is secured in said chamber, said wire being threaded through the passage in said member to anchor the same, whereby the tension of said wire may be adjusted by rotation of said member in the container.

10. The combination with an incandescent lamp having a filament and base of an annular container secured about said base, a permanent magnet, and an armature therefor within said container, said armature being electrically connected with said base, a pair of lead wires for said filament, one of said wires being connected to the insulated terminal of said base and the other of said lead wires being insulated from said base and terminating within said container in a position to be engaged by said armature when in attracted position, said armature and the end of said last mentioned lead wire being each silver plated to serve as cooperating contacts, and an expansible resistance wire within said container connected between said silver plated end of the lead wire and the armature, said wire, when cold mechanically preventing movement of said armature to attracted position.

11. The combination according to claim 7 including means biasing said armature carried contact into position to engage the other of said contacts, said biasing means comprising a resilient conducting member forming a part of the electrical connection between said armature carried contact and said base.

12. The combination according to claim 7 including means biasing said armature carried contact into position to engage the other of said contacts, said biasing means comprising a resilient conducting member forming a part of the electrical connection between said armature carried contact and said base, said biasing means being secured at one end to said container and connected at its other end to said expansible resistance wire.

13. The combination according to claim 7 including a resilient conducting strip biasing said armature carried contact into position to engage the other of said contacts, said strip being secured at one end to said container and connected at its movable end to said expansible resistance wire, said armature being carried by and secured to the strip at a point remote from the movable end, said strip for a substantial length thereof being of a curved cross section, concave toward the armature whereby, upon expansion or contraction of said wire, said strip moves substantially throughout its length to cause positive closing or opening of said contacts.
